(57) **CLAIM**

The ornamental design for a heat-sealed waste disposal, as shown and described.

DESCRIPTION

FIG. 1 is a perspective view of the heat-sealed waste disposal;
FIG. 2 is a front side elevational view thereof;
FIG. 3 is a side elevational view thereof, the opposite side view being a mirror image thereof;
FIG. 4 is a rear side elevational view thereof; and,
FIG. 5 is a top plan view thereof.
